UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

Application filed December 12, 1921. Serial No. 521,666.

To all whom it may concern:

Be it known that I, MALCOLM L. COSSITT, a citizen of the United States, residing at Alameda, in the county of Alameda and State 5 of California, have invented certain new and useful Improvements in Manifolding Attachments for Typewriters, of which the following is a specification.

My invention relates to manifolding attachments for typewriters, comprising one or more manifolding members, with means carried by the platen-carriage of the machine, for moving said members into and out of functional position in the line of type- 15 impact.

One of the objects of my present invention is to provide for moving the manifolding member to and from functional position in an arcuate path parallel with the axis of 20 the platen, so that when out of use said member is in a vertical position at one end of the platen.

Another object is to adapt the movement above noted for use in conjunction with a 25 second movement of the manifolding member in an arcuate path perpendicular to said first named movement. Another object is to provide a simple, cheap and effective 30 guide-member for directing the manifolding member outwardly from a chambered platen in which it is housed and from which it is adapted to be drawn for presentation in functional position.

With these objects in view, my invention 35 consists in the novel manifolding attachment for typewriters which I shall now fully describe, by reference to the accompanying drawings, in which—

Fig. 1 is an end elevation of my manifolding attachment.

Fig. 2 is a top plan, broken, of the same.

Fig. 3 is a front elevation, broken, of the same.

Fig. 4 is a longitudinal section of the 45 chambered end of the platen, on the line 4—4 of Fig. 1, showing the manifolding members housed therein.

Fig. 5 is a section on the line 5—5 of Fig. 4.

Fig. 6 is a perspective view of the manifolding ribbon spools and the skeleton wire-guide for the ribbons.

Fig. 7 is a perspective view of the impal-

ing lug at the free end of the manifolding ribbon carrier rod.

Fig. 8 is a perspective view of the hinge connection of the carrier rods with the carrier arm of the manifolding ribbon.

Fig. 9 is a sectional detail of said hinge showing a means for yieldingly controlling it.

Fig. 10 is a perspective detail of the pintle of the controllable hinge.

Fig. 11 is a view showing the manifolding ribbon carriers adapted for arcuate 65 movement only in a plane parallel with the platen axis.

1 indicates the platen carriage of a typewriter and 2 the platen, having a shaft 3 for turning it for line-spacing, as usual.

The platen 2 has at one end a chamber 4, as seen in Figs. 4 and 5, in which is housed a spool 5, mounted for independent rotation upon the platen shaft 3. Upon this spool is wound a manifolding member 75 6 of suitable nature and shape, say, for example, in the form of a ribbon. There may be a plurality of these spools and ribbons, here shown as two.

Upon a fixed bar 7 of the platen carriage is secured a bracket 8, Figs. 1 and 2, which is secured as by means of screws 9, Figs. 1 and 4, to the head of a sleeve 10 within the chamber of the platen. To this sleeve is secured a skeleton guide member 11, having inclined direction bars 11', over which the ribbons pass from the spools 5, as seen in Fig. 6. This guide member is made of wire and its angular direction bars 11' are at different levels to adapt them to severally 90 receive and guide the two manifolding ribbons in non-interfering parallel planes, out from the platen end through an aperture 10' in the head of the sleeve 10, as shown in Fig. 4.

12 is a carrying arm, pivoted at 12' to the fixed bracket 8, and adapted to move in an arcuate path in a plane transverse to the platen axis. The free end of this arm is provided with spaced guides 13, Fig. 4, one 100 for each ribbon, the forward edges of said guides having impaling teeth—Fig. 1. To the upper portion of the free end of said arm 12 are hinged by means of the cross pintles 14, Fig. 8, two rods 15, which extend, as 105 shown in Figs. 2 and 3, parallel with the

platen. The free end of each rod is provided with a toothed guide lug 16, such as is shown in Fig. 7.

The operation of the attachment is as follows:—In the relatively permanent non-functional position, the arm 12 and its rods 15 are elevated above and back of the platen, the rods being parallel with the platen. The manifolding ribbons 6 are drawn from their spool mounts housed within the platen, the skeleton guide member 11 directing their course outwardly to the end of the platen, and said drawn out portions or sections of the ribbons are passed through the guides 13 of the arm 12 and over the impaling fronts thereof, and thence over to and through the impaling guides 16, on the free ends of the rods 15. The ribbons are temporarily impaled upon the teeth of the guides whereby they are releasably held under proper tension. When the ribbons are needed for making carbon copies, the arm 12 is brought down through an arcuate path, about its pivotal center at 12'; both rods 15 and ribbons 6 accompanying it, until the ribbons reach their functional position in front of the platen in the line of type impact. A reversal of this movement carries them out of use.

But if the non-use of the ribbons is to be relatively temporary, or for any other reason it be found not desirable to throw them up by the movement of the arm 12 as above described, they or either of them may be turned out of use by taking hold of the free end of the rods 15 and turning said rods about their pivot pintles 14, so that said rods and ribbons rise in an arc in a vertical plane parallel with the platen, until they stand upright at one end of the platen, as is indicated by the dotted lines in Figs. 1 and 3; and from this position they may be turned down again for use. In order to hold the parts at the limits of this movement, the pivot pintles 14 of the rod hinges are releasably locked by suitable means, as, for example, by the notches 17 and spring pressed balls 18, shown in Figs. 9 and 10.

Thus the ribbons may be thrown into and out of use by arcuate movements in planes perpendicular to each other. In practice the first movement, that is to say, with the arm 12, may be employed for a more permanent disuse of the ribbons, while the last movement, namely that with the rods 15, is convenient for temporary purposes. When the portion or section of the manifolding ribbon stretched between the guides 14 and 16 is used up, it is released from the impaling teeth of said guides and a fresh portion is drawn out from the spool housed in the platen, until it lies between said guides and is then again impaled thereon, the used section or portion being cut or torn off. In this successive drawing out of fresh portions,

the skeleton guide-member 11 within the chambered platen effectively directs the course of the ribbon, while in the case of plural ribbons, said member keeps them apart so that they do not interfere with each other.

In Fig. 11, I show a modification in which the carrying arm 12 and bracket 8 are integral, so that said arm has no arcuate movement but is permanently horizontal. The arm, however, carries the two hinged rods 15 as before, and in this case, the ribbons have only a single arcuate movement in a vertical plane parallel with the platen. The dotted lines show the elevated position of said rods.

Although, as stated hereinbefore, the ribbons carried by and between the end of the arm 12 and the ends of the rods 15 are held under tension by being releasably impaled, said ribbons, under the blows of the type tend to slacken during use. This is overcome by making the rods 15 slightly resilient or springy in their length. In initially impaling the ribbon on the lug 16 at the free end of the rod, said rod is slightly flexed, and is so held by the impaled ribbon. Then as the ribbon tends to slacken from use, the resiliency of the rod automatically takes up the slack, so that, in addition to the initial tension due to impaling it on the toothed members, there is the automatic constant tension strain due to the flexed resilient rod.

I claim:—

1. A manifolding attachment for typewriters comprising a manifolding member; and a rod by which said member is carried, said rod being associated with the platen-carriage of the machine by a hinge connection at one end adapting it to move said member in an arcuate path parallel with the platen axis from vertical position at one end of the machine platen to a horizontal position in the line of type impact, and back again.

2. A manifolding attachment for typewriters comprising a manifolding member; an arm associated with the platen carriage of the machine at one end of and transverse to the platen; a rod carried by the arm and extending parallel with the platen; means for carrying the manifolding member between the free end of said arm and the free end of said rod; and a hinge connection between said rod and arm adapting the rod for movement in an arcuate path from a vertical position to a horizontal position and return, to carry the manifolding member into and out of the line of type impact.

3. A manifolding attachment for typewriters comprising a manifolding member; an arm associated with the platen-carriage of the machine at one end of and transverse to the platen; a rod carried by the arm and extending parallel with the platen; means

for carrying the manifolding member between the free end of said arm and the free end of said rod; a hinge connection between said rod and arm adapting the rod for 5 movement in an arcuate path from a vertical position to a horizontal position and return; and a pivotal connection for the arm adapting it for movement in an arcuate path perpendicular to the path of movement of the 10 rod about its hinge connection.

4. In a manifolding attachment for typewriters, the combination of a chambered platen; a manifolding member housed within the chamber of the platen and adapted 15 to be drawn out therefrom for presentation in functional position in the line of type impact; a non-rotatable member housed within the platen chamber, formed of wire with angular cross portions for guiding the 20 manifolding member in its outward course, and means mounted on the platen carriage of the machine for holding the drawn out manifolding member in functional position.

5. A manifolding attachment for typewriters comprising an arm associated with 25 the platen carriage of the machine at one end of the platen; a resilient rod extending parallel with the platen and hinged to said arm, adapting it for movement in an arcuate path in a plane parallel with the platen 30 axis; and a manifolding member carried by and between the arm and the free end of the resilient rod.

6. A manifolding attachment for typewriters comprising a resilient rod associated 35 with the platen carriage of the machine and adapted for movement in an arcuate path parallel with the platen axis; and a manifolding member carried by said rod under tension due to the resilient flexing of said 40 rod, and adapted to be moved into and out of functional position by the movement of the rod.

In testimony whereof I have signed my name to this specification.

MALCOLM L. COSSITT.
